UNITED STATES PATENT OFFICE.

ELMER ELLSWORTH BOWER, OF ROCHESTER, MINNESOTA.

AUTOMOBILE SIGNAL.

Application filed February 5, 1926. Serial No. 86,270.

This invention relates to automobile signals of that type adapted to be situated close to the driver so that the same can be actuated readily while the vehicle is in motion.

One of the objects of the present invention is to provide a simple and compact structure for use primarily on closed vehicle bodies and including a foldable signal member which, when not in use is housed within a container provided therefor so as thus to be protected from the weather.

A further object is to provide a signal device which, when unfolded and in use simulates a hand.

A still further object is to provide a signal device easy to operate and which does not detract from the appearance of the vehicle to which it is attached.

With the foregoing and other objects in view which will appear as the description proceeds, the invention resides in the combination and arrangement of parts and in the details of construction hereinafter described and claimed, it being understood that changes in the precise embodiment of the invention herein disclosed may be made within the scope of what is claimed without departing from the spirit of the invention.

In the accompanying drawings the preferred form of the invention has been shown.

In said drawings,

Figure 1 is an elevation of the signal device, its housing being shown open and in section and a portion of a supporting structure being also shown in section.

Figure 2 is a view similar to Figure 1 showing the signal device folded and housed.

Figure 3 is a section on line 3—3 Figure 1. Referring to the figures by characters of reference 1 designates an elongated housing which is formed of metal. This housing is adapted to be arranged substantially vertically upon a portion of the vehicle body indicated generally at B. The housing is provided with a hinged door 2 to which is connected a spring 3 secured in the housing and serving to hold the door normally open. This spring is supported close to one of the walls of the housing where it will not interfere with the operation of the parts constituting the signal mechanism.

Superposed pivots 4 and 5 are arranged within the upper portion of the housing at equal distances from the open side thereof and mounted on the upper pivot 4 is an elongated strip 6 while another elongated strip 7 is mounted on the pivot 5. These strips are pivotally connected, at intermediate points to a connecting strip 8, as shown at 9 and, as illustrated particularly in Figure 3, the said connecting strip is stepped in the direction of its length. To the connecting strip are pivotally connected intermediate strips 10 and these strips 10 are connected to each other and to the strips 6 and 7 by short links 11. The outer end portions of the strips 6, 7 and 10 are shaped to simulate the fingers of a hand. A short strip 12 simulating the thumb of a hand is pivotally connected to the strip 6 close to the connecting strip 8, as shown at 13 and at a point below the pivot 13 this strip 12 is connected to a rod 14 which projects into the upper portion of the housing 1 and is mounted on a pivot 15 located close to but slightly above the pivot 4. A spring 16 engages the strip 6 and is preferably coiled about the pivot 4, one end of this spring bearing against the inner wall of the housing 1 as shown particularly at 17. Thus the spring serves to hold strip 6 normally elevated and projected laterally from the housing 1 as shown in Figure 1. When the strip is thus supported the other strips 7 and 10 are held in extended positions as shown in Figure 1 and the thumb strip 12 is also held extended outwardly and upwardly.

A bracket 18 is attached to the inner side of the structure B and has a sleeve 19 pivotally connected thereto. An operating rod 20 is slidably mounted within this sleeve 19 and is provided at one end with a knob 21 or the like whereby it can be actuated readily by the occupant of the vehicle. The other end of the rod projects into the housing 1 and is connected by a spring 22 and a few chain links or the like indicated at 23, to the arm 6. An opening C is formed in the structure B so that the rod can work therein, this opening also receiving a link 24 one end of which is pivotally connected to the sleeve 19 as indicated at 25. The other end of the link is connected by a link 26 or the like to an ear 27 projecting from

a rod 28. This rod is pivotally mounted at one end within the upper portion of the housing 1 while its other end is pivotally and slidably mounted within a bracket 29 secured to the cover or door 2.

When it is desired to collapse or fold the signal arm the operator pulls the knob 21 and motion will be transmitted therefrom through the link 23 and spring 22 to strip 6 which, in turn, will transmit motion through link 11 and the connecting strip 8 to the other strips 7 and 10. Consequently these strips will be folded to position one beside the other within the housing 1 as shown in Figure 2. During this downward swinging movement of the signal arm the rod 14 will pull upon the heel portion of the strip 12 and cause said strip to be pulled or swung relatively to the strip 6 and assume a position at one side thereof. Consequently all of the strips will thus be brought to position within the housing which will be of ample proportions to properly hold them. When the signal arm is thus folded and housed the end of the rod 20 to which the spring 22 is connected will have been brought to position close to the sleeve 19. Consequently the operator can then swing the knob 21 and rod 20 downwardly to the position shown in Figure 2. This will result in a leverage being exerted upon the strip 24 which will pull through its connection 26 upon the rod 28 and cause the door 2 to swing to closed position. Here it will be held firmly as long as the rod 20 is in its downwardly extended position because, at this time, the pivot 25 is past the dead center and it becomes impossible for the door to swing open until the rod 20 has been swung upwardly to move the pivot 25 past the dead center. At that time the spring 22, which has been held under tension, will act to pull the rod 20 longitudinally through the opening C, this motion being transmitted from the arm 6 which is thrown upwardly by the spring 16. At the same time the door 2 is opened by the spring 3 because, when rod 20 is brought to its outwardly extended position, the rod or strip 24 is also brought into the opening C and allows the door to open without hindrance.

Obviously by providing a device such as described the hands of the driver are free at all times for operation of the car.

What is claimed is:

1. A device of the class described including a housing, a door therefor, a foldable signal arm pivotally mounted within and normally extended laterally from the housing, an operating member slidably and pivotally mounted, means actuated by the sliding movement of said member for folding the signal arm into the housing, independently of the movement of the door, means

operated by the pivotal movement of the member for closing the housing, said member when brought to the limit of its swinging movement in one direction constituting means for locking the arm in folded position 70 and for holding the housing closed.

2. The combination with a housing and a door for closing the same, of a signal arm comprising pivotally mounted strips, connections therebetween, said strips and connections cooperating when extended from the housing to simulate a hand, an operating member pivotally and slidably mounted, a resilient connection between said member and one of the strips for swinging the strips 80 and their connections into the housing during the sliding movement of the operating member independently of the movement of the door, and means actuated by the pivotal movement of said member for closing the 85 door of the housing while the strips are within the housing.

3. The combination with a housing, a door, and yielding means for opening the door, of a signal arm including spaced strips 90 pivotally mounted within the housing and connections between the strips, said strips and connections being movable relative to each other when swung in one direction, to assume positions side by side within the 95 housing, an operating member mounted for sliding and swinging movement, means actuated by the sliding movement of said member for swinging the strips into the housing, while the door is stationary in open position 100 and means operated by the swinging movement of said member for closing the door of the housing.

4. The combination with a housing and a door therefor of spaced strips pivotally mounted within the housing, pivotally mounted connections therebetween, said strips and connections cooperating to form a signal arm when in normal position, yielding means engaging one of the strips for holding the arm in normal position, an actuating member mounted for sliding and swinging movement, means operated by the sliding movement of said member for swinging the strips and connections into positions 110 side by side within the housing, while the door is stationary in open position, means operated by the swinging of the actuating member for shutting the door of the housing and to fasten said door in closed position. 120

5. The combination with a housing and a door therefor, of separate strips hingedly mounted within the housing, pivotally mounted means connected to said strips and co-operating therewith to form a signal arm, an actuating member mounted for sliding and swinging movement, means operated by the sliding movement of said member for swinging the strips and their connections in- 130

to positions side by side within the housing, while the door is stationary in open position, means operated by the swinging movement of the actuating member for shutting the door of the housing and holding it in closed position, and separate spring means released by the swinging movement of the

actuating member in one direction for automatically opening the door and bringing the signal arm to active position.

In testimony that I claim the foregoing as my own, I have hereto affixed my signature.

ELMER ELLSWORTH BOWER.
